UNITED STATES PATENT OFFICE

94,468

DESIGN FOR A COMBINATION SHEATH FOR A HUNTING KNIFE AND AX

John Russell Case, Bradford, Pa.

Application August 27, 1934, Serial No. 53,076

Term of patent 7 years

To all whom it may concern:

Be it known that I, John Russell Case, a citizen of the United States, residing in the city of Bradford, in the county of McKean and State of Pennsylvania, have invented a new, original, and ornamental Design for Combination Sheath for a Hunting Knife and Ax, of which the following is a specification, reference being had to the accompanying drawing, forming a part thereof.

Fig. 1 is a front elevation of a combination sheath for a hunting knife and ax, showing my new design; and Fig. 2 is a side elevation of the same.

The specific use for which the sheath is designed is to accommodate a utensil composed of a knife having a detachable blade and an ax part arranged to be inserted in the handle in place of the blade when it is desired to use the ax.

What I claim is:

The ornamental design for a combination sheath for a hunting knife and ax, substantially as shown and described.

JOHN RUSSELL CASE.
